Patented Sept. 22, 1925.

UNITED STATES PATENT OFFICE.

LEWIS R. BARBER, OF FRESNO, CALIFORNIA.

VENTILATING AND HEATING DEVICE.

Application filed May 27, 1924. Serial No. 716,212.

To all whom it may concern:

Be it known that I, LEWIS R. BARBER, a citizen of the United States, residing in the city of Fresno, in the county of Fresno and State of California, have invented a new and useful Improvement in a Ventilating and Heating Device, of which the following is a specification.

My invention relates to improvements in ventilating and heating devices for houses and the like whereby a current of either cool or warm air may be forced into a room or rooms to maintain a constant supply of fresh air at a desired temperature.

The primary object of my invention is to provide an improved ventilating device operable to maintain a fresh air supply at a desired temperature.

Another object is to provide an improved device which will form an efficient means for cooling or heating a room or rooms.

A further object is to provide an improved structure which may be economically manufactured and installed, which will occupy but a small amount of space, and which may be easily controlled from a point relatively remote from the device.

I accomplish these and other objects by means of the device disclosed in the drawings forming a part of the present specification and drawings wherein like characters of reference are used to designate similar parts throughout said specification and drawings and in which,

Fig. 1 is a broken side elevation of my improved ventilating and heating device, parts being broken away and shown in section.

Fig. 2 is a transverse section taken upon the line 2—2 of Fig. 1 in the direction indicated.

Fig. 3 is a longitudinal section through the gas and air passages.

Fig. 4 is a broken side elevation of a modified form of the furnace as adapted for use with electrical heating elements.

Figs. 5 and 6 are transverse section views taken upon the lines 5—5 and 6—6 respectively of Fig. 4 in the directions indicated.

Referring to the drawings my improved ventilating and heating device will be seen to consist of an outer casing 1 within which is mounted an inner casing 2. An outlet passage 3 is connected to one end of the outer casing 1, said passage being arranged to communicate with one or more rooms as desired. A fan 4 is mounted in connection

with an opening 6 formed in the opposite end of the outer casing to force a current of air through the furnace and outlet passage for a purpose hereinafter more fully described. The fan 4 may be of any desired type or construction, the ordinary ventilating fan as illustrated in the drawings and driven by an electric motor 7 being well adapted for the purpose, the blades of the fan being positioned within an annular flange 8 around the opening 6 to cause the air current set up by the fan to be forced directly through the casing 1.

In the preferred form of my invention disclosed in Figs. 1 and 2 of the drawings, a pair of burners 9 are mounted within a compartment 11 formed within the lower portion of the outer casing 1, said burners being arranged directly below openings 12 formed in the bottom of the inner casing. An air passage 14 is mounted within the inner casing 2 the sides, top, and bottom of said air passage being arranged in spaced relation to the corresponding portions of the inner casing. A gas passage 16 is mounted within the air passage 14, said passage 16 communicating with the space between the air passage and the inner casing 2 through passages 17 and 18 arranged near the ends of the passage 16 whereby products of combustion from the burners 9 may pass upwardly around the air chamber and thence into the gas passage 16. The passage 17 is made larger than the passage 18 so that a greater amount of the combustion products will be drawn into the passage 16 at the end near the fan thereby causing a greater amount of heat to be imparted to that portion of the device from which heat is most rapidly imparted to the passing air current.

Partitions 19 mounted within the outer casing 1 close the ends of the inner casing 2, and form supports for the inner casing 2, the air passage 14, and the gas passage 16, openings 21 being formed in said partitions to match with the air passage 14, said partitions also affording a clear passage between the adjacent sides of the inner and outer casings. A gas vent 22 communicated with the gas passage 16 through the partition 19 the end adjacent the outlet passage 3, said vent 22 being mounted within said outlet passage 3 and carried therealong to a point relatively remote from the casing 1, at which point it is extended outwardly through a suitable opening 23 in the side of the pas-

sage 3 and carried in any convenient manner to a chimney or the like.

The burners 9 are preferably supplied with fuel of any suitable character through pipes provided with valves 26 adapted to be operated by rods 25 or by other suitable means whereby the burners may be regulated from a point relatively remote from the burner. The pipes 24 are introduced 10 into the compartment 11 through openings 27 formed in one side thereof. An opening 28 is also provided to admit air and to facilitate the adjustment of the burners.

In operation, the device is mounted in 15 any convenient location, preferably in the basement of a house, the burners being connected to a source of fuel and the motor connected to a source of electrical energy 20 in any convenient manner. When the motor is operated to drive the fan a current of air will be forced through the casing 1, said current of air passing through the air passage 14 and through the space between the inner and outer casings and then through 25 the outlet passage 3 to the room to be ventilated, thereby directing a continuous supply of fresh air into the room. During hot seasons of the year, cool air will thus be drawn from the basement of the house and 30 circulated through the room or rooms to which the outlet passage 3 is connected. If desired the air may be cooled by artificial means as by placing ice within the path of the current of air to or from the fan, in this 35 manner increasing the cooling effect obtained. During cold seasons, the air directed to the room may be readily and efficiently heated by means of the burners 9 thereby causing the room to be kept heated by a 40 continuous supply of fresh warm air.

The structure of the casings and passages above described is particularly adapted to obtain an efficient heating of the air. In this connection it will be noted that the burners 45 are arranged below the inner casing 2 in such a manner that the flame and the products of combustion are directly upwardly through the openings 12 against the bottom of the air passage 14, a baffle 29 being preferably secured adjacent the bottom of said air passage to prevent said bottom from being damaged by the heat. The heat combustion products pass upwardly around the sides of the air passage between the walls 50 of the inner casing 2 and the walls of said air passage, thus serving to heat the walls of both the inner casing and the air passage. The combustion products are then drawn through the passages 17 and 18 into the gas 55 passage 16 thereby causing the walls of the air passage and the walls of the gas passage to be heated. From the gas passage the combustion products are drawn through the vent 22. In this manner the walls of the inner casing 2, the air passage 14 and the

gas passage 16, and finally the vent 22, are all heated thereby affording a very large area from which heat is radiated to the current of air forced therewith by the fan 4. The air will thus be effectively heated 70 and a supply of fresh warm air directed into the room or rooms to which the outlet passage 3 is connected.

By mounting the device immediately below the floor, the rods 25 by which the burner valves 26 are operated may be carried upwardly into the room above whereby the burners may be conveniently controlled from the room. In like manner, the electrical connections to the motor 7 may be controlled by a suitable switch located in the room so that the fan and burners may be controlled from a point relatively remote from the device.

Suitable igniting means such as pilot 85 burners or electrical igniters of any suitable construction, not shown, are mounted in connection with the burners and preferably arranged to be operated from a point near the other controls of the furnace. 90 However, as such igniting means are well known in the art and can form no part of the present invention a detailed description is herein unnecessary.

In the modified form shown in Figs. 4, 95 5, and 6, I have shown an arrangement whereby the air may be heated by electrical heating elements in place of the burners above described. In this form of the invention the air passage and gas passage is 100 omitted, the air current being forced directly through the inner casing 2, and past a plurality of electrical heating elements 31 extending longitudinally through the inner casing 2. The elements 31 are preferably supported upon brackets 32 secured upon the partitions 33 and arranged to receive suitable electrical connections, not shown, said connections being accessible through a door 34 formed in the adjacent portions of 105 the outlet passage 3. In this form of the invention a plurality of baffles 36 are mounted within the outer casing 1 between the fan 4 and the heating elements 31 to impart a 110 whirling motion to the air current whereby the air will be more thoroughly and effectively heated by the heating elements 31. The operation of this form of the device is the same as above described in connection with the preferred form of the invention, cool air from the basement of a house being forced into the room or rooms to which the outlet passage 3 is connected for 115 cooling and ventilating said rooms during hot seasons, and air warmed by the heating elements 31 being similarly directed into the room or rooms to heat and ventilate said rooms during cold weather. In this type 120 of my invention, the electrical controls, not shown, may be positioned at any convenient 125 130

place and the fan and heating elements independently controlled to regulate the temperature and ventilation of a house.

Having thus described my invention what I claim as new and desire to secure by Letters Patent is,

1. A ventilating and heating device comprising an outer casing; an inner casing mounted within the outer casing; an air passage mounted within the inner casing; burners mounted below the inner casing for heating said inner casing and the air passage; a gas passage mounted within the inner casing, said gas passage communicating with the space between the air passage and the inner casing through passages opening into the top of the gas passage whereby combustion products from the burners may be drawn upwardly past the sides of the air passage and into the gas passage; an outlet passage connected to one end of the outer casing and communicating with a room; a fan mounted in connection with the opposite end of the outlet casing and adapted to force a current of air past the inner casing and gas passage and through the air passage and outlet passage to the room for ventilating and regulating the temperature of the room; and a gas vent connected to the gas passage and extending outwardly therefrom through the outlet passage and carried outwardly through a side of said outlet passage at a point relatively remote from the casings whereby air moving

through the outlet passage may be further heated by contact with said vent.

2. A ventilating and heating device comprising an outer casing; an inner casing mounted within the outer casing, said inner casing having walls and ends in spaced relation to the walls and ends of the outer casing; an air passage mounted within the inner casing and having walls spaced from the walls of said inner casing; burners mounted below the inner casing for heating said inner casing and the air passage; a gas passage mounted within the air passage, said gas passage communicating with the space between the air passage and the inner casing through passages opening into the top of said gas passage whereby combustion products from the burners may be drawn upwardly past the sides of the air passage and into the gas passage; partitions closing the ends of the inner casing and gas passage and having openings matching with the air chamber; an outlet passage connected to one end of the outer casing and communicating with a room; and a fan mounted in connection with the opposite end of the outer casing and adapted to force a current of air past the inner casing and the gas passage and through the air passage and outlet passage to the room to ventilate and heat the room.

In witness whereof I hereunto set my signature.

LEWIS R. BARBER.
